(57) **CLAIM**

The ornamental design for an air intake for automotive applications, as shown and described.

DESCRIPTION

FIG. 1 is a top front perspective view of the air intake for automotive applications showing my new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

In the drawings, the evenly spaced broken lines shown in the figures depict portions of the air intake for automotive applications that form no part of the claimed design. The dash-dot-dash broken lines define the boundary of the claimed design and form no part of the claimed design.
